[57] **CLAIM**

The ornamental design for portable electric chamfering machine, as shown.

DESCRIPTION

FIG. 1 is a top, front and right side perspective view of a portable electric chamfering machine showing our new design;

FIG. 2 is a right side elevational view thereof;

FIG. 3 is a front elevational view thereof;

FIG. 4 is a rear elevational view thereof;

FIG. 5 is a left side elevational view thereof;

FIG. 6 is a top plan view thereof; and,

FIG. 7 is a bottom plan view thereof.

FIG. 1

FIG. 2

FIG. 3

FIG. 4

FIG. 5

FIG. 6

FIG. 7
